TEMPERATURE MEASURING DEVICE

Irving Lorenzo Canuteson, Beaumont, Tex., assignor to Precision Scientific Company, Chicago, Ill., a corporation of Illinois

Application April 29, 1937, Serial No. 139,808

11 Claims. (Cl. 73—354)

This invention relates to a device, termed a "temperature thief", for measuring the temperature of oils and other liquids. Devices of this type consist in general of an open bowl having a thermometer associated therewith adapted to be lowered into a tank of liquid and including means for closing the bowl to entrap a sample of the liquid and for raising the bowl to the surface to obtain a temperature reading. By taking samples 10 of the liquid at various points and at different elevations throughout the tank it is possible to obtain its mean temperature from which to compute the normal volume of the liquid in the tank at some designated basic temperature, and, by 15 analysis, to determine the average composition or quality of the liquid.

In devices of the above character, it is necessary that the bowl be of simple and sturdy construction, easy to manipulate and positive in operation. To obviate false temperature readings that enter cumulatively into the final volumetric determination it is of the utmost importance that the bowl be absolutely fluid-tight after closing to avoid contamination of the entrapped sample by 25 the surrounding body of liquid through which it is raised and to prevent evaporation of the sample after the bowl has been removed from the tank for the purpose of reading the thermometer.

It is an object of my invention to provide a 30 temperature thief incorporating the above-mentioned advantages, which includes a bowl spring-supported upon a suspension rod carrying a valve disk adapted to close an inlet in the bottom of the bowl under the urge of the spring and also including a latch for retaining the bowl against the pressure of the spring but releasable upon a jerk of the suspension rod to raise the bowl into closed position with the valve and entrap a sample of liquid therein.

A further object of my invention is to provide 40 in a temperature thief of the above character a latching mechanism for retaining the bowl and suspension rod in relatively displaced position with the spring under compression and including a detent transversely slidable upon one of said members and engaging a ledge upon the other member and retained against disengagement solely by the frictional contact resulting from the pressure exerted by the spring. By this arrangement, when a jerk is imparted to the suspension rod transmitted by the operator through the cord by which the device is lowered into the tank of liquid, the spring is momentarily further compressed to relieve the frictional contact between the detent and ledge and to cause means to be-

come operative to slide the detent out of latching engagement with the ledge. Preferably I provide a spring member to slide the detent when the latch is released, but a cam, or both a cam and a spring, may be provided for this purpose. 5

In the preferred form of my invention the bowl is provided with a second inlet opening in its top and includes a floating valve which is adapted to be supported above its inlet when the apparatus is latched open but which seats by gravity 10 and closes this inlet when the latch is released. By reason of the virtually independent operation of the valves, one valve cannot interfere with the tight seating of the other valve such as is likely to occur, due to expansion, in certain types of 15 temperature measuring devices in which the valves are rigidly connected for unitary operation.

Other objects and advantages will be apparent from the following detailed description of a 20 preferred embodiment of the invention, reference being had to the annexed drawings in which:

Figure 1 is a vertical cross-sectional view through a temperature measuring device of the type used in obtaining the temperature of oils, 25 the valves being shown in full lines in open position and in dotted lines in closed position;

Figure 2 is a view in side elevation of the temperature measuring device of Fig. 1;

Figure 3 is a view in cross-section on the line 30 3—3 of Fig. 1 through the rod forming an armor for the thermometer tube;

Figure 4 is a cross-sectional view through the latching mechanism on the line 4—4 of Fig. 1;

Figure 5 is a cross-sectional view through the 35 cage surrounding the thermometer well on the line 5—5 of Fig. 1; and

Figure 6 is a modified form of latching mechanism and showing the latch in sprung or released position. 40

The temperature thief illustrated in the drawings comprises a generally cylindrical bowl 1 and a hollow suspension rod 2 extending axially upwardly therefrom through the top of the bowl. Within the rod 2 is housed a thermometer tube 3, 45 the rod providing an armor for the tube and having a window 4 of magnifying glass extending throughout a substantial portion of its length to permit inspection of the thermometer which is calibrated in the usual manner, for example, 50 from 0° to 180° F. The rod 2 is closed by a cap 5 screwed into its upper end and this plug is formed with transverse finger lugs 5a and an eye 6 for the attachment of a suspension cord for lowering the device into a tank of liquid and for 55

closing its inlets in a manner which later will be described. To the lower end of the rod 2 and constituting a prolongation of the suspension rod is threadedly secured, as at 7, a hollow valve rod 5 2a transversely recessed throughout the major portion of its length (see Fig. 5) and serving as a cage for the well end 3a of the thermometer tube 3.

The bottom of the valve rod is formed as a 10 valve disk 10 having a tapered periphery from which depend a plurality of guide fingers 10a. This valve serves to close an inlet opening 11 in the bottom of a cup 12 constituting a detachable nose piece threaded upon the lower end of 15 the bowl 1 and forming a part thereof. The inlet 11 where it opens into the container is circumferentially tapered to present a seat 11a for the complementary tapered valve disk 10. A liner 1a of bakelite or other thermally non- 20 conductive material extends into and overlies the inner circumference of the bowl 1 to retard the transmission of heat through the walls of the bowl.

This bowl is supported at its top by a spider 25 14 comprising four radical arms 14a extending outwardly from a central cylindrical hub 15 and secured by a tongue-and-slot fit to arms 17 projecting upwardly from the rim of the bowl. A screw 16 retains the spider and arms against 30 relative shifting movement. The hub is formed with an oversize axial bore to receive the suspension rod, the clearance space surrounding the latter providing a spring chamber 18. The upper end of this spring chamber is closed by an 35 inwardly directed flange 18a snugly but slidably surrounding the end of the rod 2. Within chamber 18 is a coil spring 19 surrounding the lower end of the rod 2 and bearing at one end against an enlarged terminal lip 20 upon the 40 end of the rod and at its other end against the flange 18a. The circumference of lip 20 is such as to slidably fit within the bore of chamber 18. By drawing the suspension rod upwardly the coil spring 19 is compressed and exerts a thrust 45 between the suspension rod and the bowl tending to move the valve seat 11a into engagement with the valve disk 10, as shown by the broken lines 10x.

In order to retain the device in set condition 50 a latch pin 21 extends radially through an opening 22 in the flange 18a. This opening is expanded upon the inner circumference of the flange to form an enlarged pocket 22a which slidably receives a detent 23 carried upon the 55 end of the latch pin 21. To the detent 23 is fastened one end of a semi-circular wire 24 of spring steel loosely received in a circumferential groove 25 in the flange 18a, as indicated in Fig. 4. The opposite end of the wire spring is pro- 60 vided with an offset portion 24a which is anchored in the wall of groove 25. A groove 25a formed in the circumference of rod 2 near its lower end provides a ledge designed to be engaged by the detent 23. The arrangement is 65 such that after the bowl and suspension rod have been displaced against the action of coil spring 19 so as to bring detent 23 in the plane with groove 25a, the latch pin 21 may be pushed inwardly by means of the knurled finger piece 70 21a against the pressure of the wire spring 24. The pressure exerted by coil spring 19 will cause the detent 23 to bear against the ledge of groove 25a with such pressure as to frictionally main- 75 tain the detent in engagement with the ledge in opposition to the pressure exerted by wire spring

24. When engagement between the detent 23 and groove 25a is momentarily relieved by a sudden jerk imparted to the suspension rod 2, which further compresses coil spring 19, the wire spring acts to slide the detent to the left (Fig. 1) to release the latch. Coil spring 19 then snaps bowl 1 sharply upward until the valve disk 10 engages its seat 11a. In order to positively insure the disengagement of the detent from its groove when the latch is operated, the lower wall of the 10 groove 25a is inclined downward and outwardly to present a cam surface 30 which cooperates with a companion inclined face 31 on the detent 23 so that when the rod 2 is jerked upwardly the cam surfaces cooperate to slide the detent in the 15 same direction as that in which a thrust is exerted by the wire spring 24.

Below the lower end of hub 15 is provided a floating valve disk 33 centrally recessed to snugly but slidably encircle a reduced circumferential 20 portion 34 of the valve rod 2a adjacent its upper end. This valve is allowed limited vertical movement along the reduced circumferential portion and is supported by a shoulder 35 upon the latter when the latch 21 is engaged. The outer circum- 25 ference of the floating valve is tapered so that upon release of the latch and movement of the bowl upwardly this tapered edge comes to rest upon the tapered seat 35a of an inlet 36 formed in the top of the bowl, and the valve closes this 30 inlet by its own weight as shown by broken lines 33x. Since the two valves 10 and 33 are not rigidly connected and operate, in a sense, independently of each other it will be apparent that any variation in the length of the suspension rod, 35 constituting parts 2 and 2a with which the valves are associated, will not interfere with the tight closing of either valve.

The manner of associating the thermometer with the rod 2 and valve rod 2a is best illustrated 40 in Figs. 1 and 2. As shown in these figures, the thermometer tube 3 is provided with a tightly fitting fibrous collar 37 somewhat above its well portion, which, after slipping the thermometer tube upwardly within the rod 2, seats within an 45 enlarged recess 38 in the upper end of rod 2a with the lower portion of the thermometer tube extending axially downward through a bore 39 into the cage 9. A closure 40 is screwed over the end of valve rod 2a and has an inturned flange 50 40a overlying the collar 37. The cap 5 is re- cessed to receive the upper end of the thermometer tube when screwed onto the top of rod 2. When the apparatus is assembled, the rod 2 will be screwed tightly down against the upper face 55 of the closure 40 so as to make fluid-tight seal therewith.

In the operation of the temperature thief de- 60 scribed above, the apparatus is latched by hold- 65 ing the bowl in the left hand with the index finger pressing against the finger piece 21a of the latch and tending to force detent 23 inwardly. With two fingers of the right hand under the lugs 5a of cap 5 the suspension rod is pulled upwardly with a spiral motion, compressing coil spring 19 65 until circumferential groove 25a in rod 2 arrives opposite the detent 23. Thereupon the detent is forced into the groove against the action of wire spring 24 and engages a ledge of the groove to latch the bowl open with the valves 10 and 33 70 supported above the inlets 11 and 36.

The bowl is now lowered into the tank of liquid to the desired level at which a temperature reading is to be obtained by means of a cord (not shown) attached to the eye 6 at the top of the 75

suspension rod 2, 2a. Since the inlets in the bottom and top of the bowl are open, this permits the rapid lowering of the bowl. The cord is then given a sharp jerk causing the suspension rod to momentarily rise against the pressure of already compressed coil spring 19 so that the ledge of groove 25a is lifted out of contact with detent 23 which permits wire spring 24 to become effective to slide the detent out of latching engagement with the groove. This causes coil spring 19 to move the bowl upwardly so as to bring valve seat 11a surrounding the bottom inlet 11 into engagement with valve 19, and to bring valve seat 36a of the inlet 36 in the top of the bowl into engagement with floating valve 33 as indicated by the broken lines 18x and 33x in Fig. 1. The bowl containing the entrapped sample of liquid may then be raised to the surface and the thermometer 3 consulted to ascertain the temperature of the sample.

In Fig. 6 is illustrated a modified form of latching mechanism differing from that just described principally in the provision of a coil spring 41 surrounding the latch pin 21 in place of the wire spring 24 shown in Fig. 4. This spring is relatively weak but has sufficient bias to slide the detent out of operative engagement with the groove 25a when frictional contact between the detent and groove is broken by an upward jerk of the suspension rod. In order to render the device more sensitive to jerks imparted to the suspension rod, the detent is formed with a conical head 42 which makes edge contact with the ledge presented by the groove. A collar 43 upon the latch pin 21 provides a stop for limiting the outward movement of the detent in its pocket 22a.

The device being open at its top and bottom creates a washing effect through the bowl while being lowered and for this reason the time in which the device will reach equilibrium with the oil is considerably shortened. If it is desired, for greater accuracy, to fill, empty and refill the device with the tank liquid before taking a temperature reading so as to equalize the temperature of the parts of the device with that of the liquid, this may be readily accomplished since to empty the device it is only necessary to raise the device slightly above the level of the liquid in the tank and momentarily lift the valve assembly against the action of spring 19.

After the latch has been tripped the valves are held tightly closed. In the case of valve 19, this valve is retained closed by the spring 19 supplemented by the weight of the entrapped sample, while in the case of valve disk 33 by atmospheric pressure and the weight of the valve disk itself. A more trustworthy temperature reading is obtained because of the relatively large volume of liquid contained in the bowl and insulating the thermometer from atmospheric temperatures when the bowl is withdrawn from the tank; and also because of the prevention of cooling by evaporation which, particularly in the case of the more volatile hydrocarbon oils, is a common source of error in determining the mean temperatures of tank liquids. I prefer to make the bowl of my device of chromium-plated bronze as I have found that this material conduces to more accurate readings than in the case of copper or brass.

It will be apparent that my invention may be embodied in other forms than that shown and described herein, and that various changes in structure and design may be made from the ex-

ample herein disclosed without departing from the spirit of my invention.

I claim:

1. A temperature measuring device comprising a bowl having inlets at opposite ends, a suspension rod extending axially through the top of the bowl, a thermometer mounted upon the suspension rod with its lower end extending into the bowl, a coil spring surrounding the suspension rod and yieldingly supporting the bowl, valves carried by the suspension rod for closing the inlets and a latch for retaining the bowl and suspension rod in displaced relation in opposition to the spring, said latch comprising a slidable detent carried by the bowl and engaging a ledge upon the suspension rod, and biasing means operable upon further longitudinal displacement of the bowl and suspension rod to slide said detent to inoperative position.

2. A temperature measuring device comprising a bowl having inlets at opposite ends, a suspension rod extending axially through the top of the bowl, a thermometer mounted upon the suspension rod with its lower end extending into the bowl, a coil spring surrounding the suspension rod and yieldingly supporting the bowl, valves carried by the suspension rod for closing the inlets and a latch for retaining the bowl and suspension rod in displaced relation in opposition to the spring, said latch comprising a slidable detent carried by the bowl and engaging a ledge upon the suspension rod, and cam means operable upon further longitudinal displacement of the bowl and suspension rod to slide said detent to inoperative position.

3. A temperature measuring device comprising a bowl having an inlet in its bottom, a suspension rod projecting axially upward through the top of the bowl, a thermometer associated with the suspension rod with its lower end disposed within the bowl, a valve upon the suspension rod adapted to close the inlet in the bottom of the bowl, a spring tending to move the bowl relative to the suspension rod and retain the inlet closed by the valve, and a latch for retaining the bowl and suspension rod displaced against the action of the spring with the valve separated from the inlet, said latch comprising a detent supported by the bowl and slidably to operatively engage a ledge upon the suspension rod, said detent being responsive to a jerk upon the suspension rod to release its engagement with the ledge and means for sliding said detent into inoperative position to permit said bowl to rise and close the inlet against the valve.

4. A temperature measuring device comprising a bowl having an inlet in its bottom, a suspension rod projecting axially upward through the top of the bowl, a thermometer associated with the suspension rod with its lower end disposed within the bowl, a valve upon the suspension rod adapted to close the inlet in the bottom of the bowl, a spring tending to move the bowl relative to the suspension rod and retain the inlet closed by the valve, and a latch for retaining the bowl and suspension rod displaced against the action of the spring with the valve separated from the inlet, said latch including a detent supported by the bowl and being slidably to operatively engage a ledge upon the suspension rod, and resilient means tending to slide the detent into inoperative position upon disengagement of the detent with the ledge by a jerk of the suspension rod to permit the bowl to rise and close the inlet.

5. A temperature measuring device comprising

- 5 a bowl having an inlet in its bottom, a suspension rod projecting axially upward through the top of the bowl, a thermometer associated with the suspension rod with its lower end disposed within the bowl, a valve upon the suspension rod adapted to close the inlet in the bottom of the bowl, a spring tending to move the bowl relative to the suspension rod and retain the inlet closed by the valve, and a latch for retaining the bowl and suspension rod displaced against the action of the 10 spring with the valve separated from the inlet, said latch including a detent supported by the bowl and engaging a ledge upon the suspension rod, said detent being retained in engagement with the ledge by the pressure of the spring, and means for sliding the detent into inoperative position upon disengagement of the detent with the ledge by a jerk of the suspension rod to permit the bowl to rise and close the inlet.
- 15 6. A temperature measuring device comprising a bowl having an inlet in its bottom, a suspension rod projecting axially upward through the top of the bowl, a thermometer associated with the suspension rod with its lower end disposed within the bowl, a valve upon the suspension rod adapted to close the inlet in the bottom of the bowl, a spring tending to move the bowl relative to the suspension rod and retain the inlet closed by the valve, and a latch for retaining the bowl and suspension rod displaced against the action of the 20 spring with the valve separated from the inlet, said latch including a detent supported by the bowl and engaging a ledge upon the suspension rod, means for shifting the detent out of engagement with the ledge upon a jerk of the suspension rod and permit the bowl to rise and close the inlet, a floating valve slidably associated with the suspension rod above the bowl and adapted to close an inlet in the top of the bowl, and a stop 25 retaining the floating valve out of engagement with the inlet in the top of the bowl when the bowl is latched in its lowered position, said floating valve upon release of the latch being designed to close said last-mentioned inlet by its own 30 weight.
- 30 7. A temperature measuring device comprising a bowl having inlets in its top and bottom, a suspension rod projecting axially upward through the top of the bowl, a thermometer associated with the suspension rod with its lower end disposed within the bowl, a valve upon the suspension rod adapted to close the inlet in one end of the bowl, a spring exerting pressure between the bowl and suspension rod and tending to retain said inlet closed by the valve, a second valve 35 encircling said suspension rod and designed to close the inlet at the opposite end of the bowl by its own weight, a latch for retaining the bowl and suspension rod relatively displaced against the action of the spring with the first-mentioned valve separated from its inlet, means associated with the suspension rod for supporting the second-mentioned valve away from its inlet when the latch is engaged, and means responsive to a jerk upon the suspension rod for releasing the 40 latch to permit the closing of the inlets by the valves.
- 35 8. A temperature measuring device comprising a bowl having inlets in its top and bottom, a suspension rod projecting axially upward through the top of the bowl, a thermometer associated with the suspension rod with its lower end disposed within the bowl, a valve upon the suspension rod adapted to close the inlet in the bottom of the bowl, a spring exerting pressure between the bowl and suspension rod and tending to retain said inlet closed by the valve, a second valve 45 encircling said suspension rod and designed to close the inlet in the top of the bowl by its own weight, a latch for retaining the bowl and suspension rod relatively displaced against the action of the spring.
- 50 9. A temperature measuring device comprising a bowl having an inlet in its bottom, a suspension rod projecting axially upward through the top of the bowl, a thermometer associated with the suspension rod with its lower end disposed within the bowl, a valve upon the suspension rod adapted to close the inlet in the bottom of the bowl, a spring tending to move the bowl relative to the suspension rod and retain the inlet closed by the valve, and a latch for retaining the bowl and suspension rod displaced against the action of the spring with the valve separated from the inlet, a stop carried by the suspension rod for supporting the second-mentioned valve away from the top inlet when the latch is engaged, and means responsive to a jerk upon the suspension rod for releasing the latch to permit closing of the bottom inlet by the first-mentioned valve under spring pressure and closing of the top inlet by floating engagement of the second-mentioned valve therewith. 55
- 55 10. A temperature measuring device comprising a bowl having inlets in its top and bottom, a suspension rod projecting axially upward through the top of the bowl, a thermometer associated with the suspension rod with its lower end disposed within the bowl, a valve disk fixed upon the lower end of the suspension rod adapted to close the inlet in the bottom of the bowl, and a floating valve disk loosely surrounding the suspension rod and seating by gravity upon the inlet in the top of the bowl, a spring exerting pressure between the bowl and suspension rod and normally tending to shift the bowl into closed position with the valve disks, and a latch 60 for retaining bowl and suspension rod longitudinally displaced and for maintaining the inlets open against the action of the spring.
- 55 11. A temperature measuring device comprising a bowl having inlets in its top and bottom, a suspension rod projecting axially upward through the top of the bowl, a thermometer associated with the suspension rod with its lower end disposed within the bowl, a valve disk fixed upon the lower end of the suspension rod adapted to close the inlet in the bottom of the bowl, and a floating valve disk loosely surrounding the suspension rod and seating by gravity upon the inlet in the top of the bowl, a spring exerting pressure between the bowl and suspension rod and normally tending to shift the bowl into closed position with the valve disks, a latch for retaining the bowl and suspension rod longitudinally displaced to maintain the inlets open against the action of the spring, and an abutment upon the suspension rod engaging the floating valve disk to retain said floating valve disk above its inlet when the bowl and suspension rod are displaced into latch engaging position.

IRVING LORENZO CANUTESON.
